UNITED STATES PATENT OFFICE.

EBERHARD L. PUPKE, OF EAST ORANGE, NEW JERSEY.

DESIGN FOR A LACING-HOOK.

42,543.

Specification for Design.

Patented May 21, 1912.

Application filed December 29, 1911. Serial No. 668,526. Term of patent 14 years.

To all whom it may concern:

Be it known that I, EBERHARD L. PUPKE, a citizen of the United States, residing at East Orange, county of Essex, and State of New Jersey, have invented a new, original, and ornamental Design for Lacing-Hooks, of which the following is a specification, reference being had to the accompanying drawing, forming a part thereof.

In this drawing Figure 1 is a perspective

view of a lacing hook embodying my new design, and Fig. 2 is a rear elevation thereof.

What I claim is:

The ornamental design for a lacing hook as shown.

EBERHARD L. PUPKE.
